UNITED STATES PATENT OFFICE.

WILLIAM MONROE WHITE, OF MILWAUKEE, WISCONSIN.

WATER WHEEL.

1,418,116.

Specification of Letters Patent. Patented May 30, 1922.

Application filed January 17, 1921. Serial No. 437,780.

To all whom it may concern:

Be it known that WILLIAM MONROE WHITE, a citizen of the United States, residing at Milwaukee, in the county of Milwaukee and

5 State of Wisconsin, has invented a certain new and useful Improvement in Water Wheels, of which the following is a specification.

This invention relates in general to improvements in the art of constructing and of operating impulse hydraulic turbines, and relates more specifically to improved means for balancing the rotors of impulse water wheels.

10 An object of the invention is to provide an impulse water wheel which is simple in construction and efficient in operation. Another object is to provide simple means for accurately balancing the rotors of impulse water wheels.

In the construction of impulse water wheels of the type in which a jet is delivered against successive buckets of a series attached to the periphery of a rotor disc, it has been found almost impossible in the past to cast or similarly form a number of steel or bronze buckets of relatively large dimensions without having the individual buckets vary in weight from five to ten per cent after they have been finished. This difference in weight of the buckets is due to various causes such as deformation of the moulds when drawing the patterns therefrom, or to improper finishing of the rough

30 castings. In order to effect the necessary balancing of the rotors, it has heretofore been customary to permit excess pieces of metal to remain upon the back of each bucket during casting thereof, and to file or chip off

40 part or all of this excess metal from the buckets in order to secure the desired final weight. It is frequently found that even the removal of this excess metal is not sufficient to reduce the weight of a bucket to that necessary in order to balance the rotor, when it becomes necessary to drill, chip or grind off metal from the body of the bucket, thereby weakening the same. Such removal of metal from the buckets, whether it be excess

50 metal or not, is also objectionable since the center of gravity of the bucket is thereby often shifted to such an extent that dynamic balancing of the rotor becomes impossible.

The present invention contemplates provision of means whereby the rotor of an impulse water wheel or the like may be

readily and perfectly balanced, regardless of the size of the rotor and without affecting the appearance and strength of the completed buckets.

60 A clear conception of an embodiment of the invention and of the method of balancing a rotor in accordance therewith, may be had by referring to the drawing accompanying and forming a part of this specification in which like reference characters designate the same or similar parts in the several views.

Fig. 1 is a side elevation of a fragment of the rotor of an impulse water wheel.

70 Fig. 2 is an enlarged central vertical section through one of the buckets of an impulse water wheel showing the improved balancing means embodied therein.

Fig. 3 is an enlarged perspective view of 75 one of the buckets of an impulse water wheel, a portion of the bucket having been broken away in order to more clearly disclose the details of the present invention.

75 The type of water wheel to which the present invention is especially applicable, comprises a rotary circular disc 3 having a series of buckets 2 secured to the periphery thereof by means of bolts passing through openings 4, 5 in the inwardly extending 80 parallel ears 12 of the buckets. Each of the buckets comprises a pair of ovoid pockets which are separated by means of a dividing edge, the dividing edges of all of the buckets lying in a common plane which is 85 coincident with the plane of the axis of the jet which during normal operation is delivered against the buckets.

90 At the rear portion of each of the ovoid pockets of each bucket, is located a strengthening rib 6 which extends inwardly away from the pocket and in line with the bucket ears 12. The ribs 6 of each bucket are connected by a transverse rib 9 which extends 95 inwardly toward the periphery of the bucket supporting disc and transversely of the rotor radii. Located adjacent to the inner wall of the transverse rib 9 are parallel guides 11 which are constructed to receive balancing weights 7, 8. The weights 7, 8 are preferably 100 formed of different sizes and held against the guides 11 and the adjacent ribs 9 by means of suitable fastening means such as rivets 10.

105 During construction of the rotor, the buckets 2 are formed and finished as has heretofore been the custom. The buckets are

then weighed individually and sufficient weights 7, 8 are added to each bucket to produce a predetermined definite weight of each bucket. By providing weights 7, 8 of 5 graded sizes, the desired final weight of each bucket 2 may be made any desired value. The weights 7, 8 are so located that they are all relatively near to the center of gravity of each bucket, thereby insuring dynamic 10 balancing of the assembled rotor. The weights 7, 8 may be readily secured in place by means of the rivets 10, and are freely removable upon removal of the rivets. The location of the weights 7, 8 is furthermore 15 within pockets provided by the ribs 6, 9 thereby positively preventing the weights from flying away from the rotor in case the rivets 10 should break. The disposition of the guides 11 at an angle to the radii of 20 the rotor, tends to produce compression of the weights, and to urge them toward the rib 9, thereby releasing the rivets 10 from stress which might otherwise be induced therein by the action of centrifugal force. 25 As the pockets within which the balancing weights 7, 8 are located, are completely closed when the rotor has been assembled, the appearance of the buckets is not undesirably affected by the addition of the weights, 30 and the outside surface of the buckets is improved by eliminating necessity of roughening as by the former method of adding or removing metal.

It should be understood that it is not desired to limit the invention to the exact details of construction and of the method herein shown and described, for obvious modifications may occur to persons skilled in the art.

40 It is claimed and desired to secure by Letters Patent:

1. A water wheel bucket having a pocket formed to permit addition or removal of weights to balance the water wheel.
- 45 2. A water wheel bucket having an enclosure formed at the back thereof by a web cast integral with the bucket pockets, and means for attaching balancing weights within said enclosure.
- 50 3. A water wheel bucket having a web cast integral with its rear portion and so disposed as to form with the periphery of the bucket supporting disc a closed pocket wherein weights may be added for balancing the bucket.
- 55 4. A water wheel bucket having detachable balancing weights secured thereto.

5. A water wheel bucket having weights secured thereto adjacent to its center of gravity.

6. A water wheel bucket comprising a rib extending transversely of the line of action of centrifugal force upon said bucket, and weights secured to the inner side of said rib.

65 7. A water wheel bucket comprising a pair of ovoid pockets, a transverse rib formed integral with said pockets, and weights secured to said rib.

70 8. A water wheel bucket comprising a pair of ovoid pockets, a rib secured to each of said pockets, a rib connecting said first mentioned ribs, and weights secured to said ribs.

75 9. A water wheel bucket comprising a pair of ovoid pockets, a rib secured to each of said pockets, and weights secured to said ribs.

80 10. In a water wheel, a bucket having pair of ovoid pockets, ribs secured to said pockets, a rotor element secured to said bucket and cooperating with said ribs to form an enclosed chamber, and a balancing weight located within said chamber.

85 11. In a water wheel, a bucket, strengthening means associated with said bucket, a support for said bucket cooperating with said strengthening means to form an enclosed chamber, and balancing means for the wheel located within said chamber.

90 12. In a water wheel, a bucket, strengthening ribs formed integral with said bucket, a support for said bucket cooperating with said ribs to form an enclosed chamber, and balancing weights for the wheel located within said chamber.

95 13. In a water wheel, a bucket, strengthening means associated with said bucket, a support for said bucket cooperating with said strengthening means to form an enclosed chamber, and balancing means for the wheel located within said chamber adjacent to the center of gravity of said bucket.

100 14. In a water wheel, a bucket, strengthening ribs formed integral with said bucket, a support for said bucket cooperating with said ribs to form an enclosed chamber, and balancing weights for the wheel located within said chamber, adjacent to the center of gravity of said bucket.

105 In testimony whereof, the signature of the inventor is affixed hereto.

WILLIAM MONROE WHITE.
